UNITED STATES PATENT OFFICE.

ORRIN A. WHEELER, OF CHICAGO, ILLINOIS.

DESIGN FOR A TOY CAP-EXPLoder.

SPECIFICATION forming part of Design No. 19,142, dated June 4, 1889.

Application filed April 2, 1889. Serial No. 305,767. Term of patent 3½ years.

To all whom it may concern:

Be it known, that I, ORRIN A. WHEELER, a citizen of the United States, residing at Chicago, in the county of Cook and State of Illinois, have invented and produced a new and original Design for Toy Cap-Exploders, of which the following is a specification, reference being had to the accompanying drawing, forming part thereof.

10 The figure is a view in elevation of my newly-designed toy cap-exploder with the hammer down.

15 The leading feature of my design consists in the comical representation of a goat butting a boy.

15 A is the handle or base supporting the figures of the boy and goat.

B is the hammer, and is made in representation of a goat, the head of which is the point of impact with the boy.

20 C is the anvil, and is made in representation of a boy, against which the head of the goat butts.

What I claim is—

25 The design for a toy cap-exploder herein shown and described, the same comprising the handle A, the trigger E, the anvil C, made in representation of a boy, and the hammer B, made in representation of a goat, as set forth.

ORRIN A. WHEELER.
